6 Claims. (Cl. 210—122.5)

This invention relates to oil refining means for association with an internal combustion engine during the operation thereof.

An object of the invention is to provide a filter unit adapted to maintain the oil supply of an engine substantially free from the usual contaminating substances which become incorporated with the oil during operation of the engine, and thus indefinitely prolong the useful life of the oil supply.

The invention contemplates the provision of a device wherein waste heat of the engine is utilized, in an exceptionally efficient and controlled manner, to heat the used oil prior to its passage in an upward direction through a body of filtering material.

Other objects and advantages will become apparent as the description of the invention proceeds with particular reference to the accompanying drawing, in which,

Figure 1 is a sectional elevation of the filter unit in accordance with the invention,

Figure 2 is a plan view of a plate member forming part of the unit,

Figure 3 is a plan view of another plate member forming part of the unit, and

Figure 4 is a diagrammatic elevation of an oil level indicating means for use in association with the invention.

Referring to the drawing, 1 is a container comprising a cylindrical member 2 and the top and bottom closure members 3 and 4, a centrally extending rod 5 with nuts 6 and 7 serving to hold the members in firmly assembled relation while permitting convenient access to the various component parts of the device.

Slightly spaced from the bottom is a fixed solid partition 8 forming a relatively small substantially closed heating chamber 9 at the base of the device. The partition is inclined at an angle of about 10° to 15° with respect to the horizontal bottom member 4. The chamber 9 receives hot combustion gases from the exhaust manifold 16 through pipe 17 and discharges them through outlet 18. Means 19 are provided in outlet 18 for adjusting the flow of gases therethrough whereby the heat supplied by chamber 9 may be regulated to some extent. It will be observed that the inlet pipe 17 is preferably positioned in the restricted portion of the chamber, while the outlet 18 is located in the enlarged portion of the chamber.

Slightly spaced above the partition 8 is a horizontally disposed perforated circular plate 10 having rods or lugs 11 thereon to position it in

spaced relation to the partition. The periphery of the plate 10 is in engagement with the inner surface of the cylindrical member 2 but is preferably unattached thereto whereby it may be readily removed from the container. The plate 10 forms an oil preheating chamber 12 extending between the plate and the partition. Oil enters the chamber 12, under normal oil pump pressure, through inlet 20, which is preferably located in the enlarged portion of the chamber.

10 Slightly spaced from the top of the device is a second perforated circular plate 13, which is also inclined at an angle of about 10° to 25° with respect to the horizontal bottom member 4. The periphery of plate 13 is in engagement with the inner surface of the cylindrical member 2 but is also preferably unattached thereto whereby the interior of the container is readily accessible on removal of the plate. Between the plates 10 and 13 is formed the relatively large filter chamber 14 containing a body of filtering material 15, and between the plate 13 and the top 3 is a relatively small oil receiving chamber 21.

An oil outlet tube 22 communicates at one end with the chamber 21 at the lower edge of plate 13, the inclination of the plate serving to direct the oil flow into the tube. Fins 23 may be provided on the plate to further assist in directing the oil flow into the tube. The other end of the tube is connected with a conduit 24 which leads the refined oil back to the engine.

In operation, the contaminated oil enters the chamber 12, where it is subjected to a substantially high temperature from the heating chamber 9. This temperature is sufficient to readily vaporize the gasoline and moisture which may be present in the oil. The inclined partition 8 ensures a non-static condition of the oil and sediment in the chamber whereby localized overheating is avoided. The preheated oil rises through the perforations in plate 10 and passes upwardly through the body of filtering material 15, where, due to its preheated condition, it is substantially entirely freed from contaminating solid matter. As the reclaimed oil rises through the perforations in plate 13 it is directed into the tube 22 and thence back to the oil circulation system of the engine. An outlet 25 may be provided in chamber 21 for the fumes and vapor.

50 If desired, means may be provided for indicating any interruption in the normal flow of oil through the device. Such means may simply comprise a conduit 26 communicating with chamber 21 and with a transparent indicating tube 27 on the dash 28 of the vehicle in which the device

is mounted. Thus, should for any reason the oil flow from the device be restricted or interrupted and the container become filled with oil, it will rise in conduit 26 and tube 21 to provide an indication of the interrupted flow.

Figure 4 illustrates another form of indicating means wherein the conduit 26 communicates with a chamber 34 containing a float 29 having thereon a contact plate 30 adapted, on rising of the float, to engage contacts 31 and close the electrical circuit 32. In the circuit 32 is located any suitable alarm means, such as a signal, gauge, bell, or light 33.

It will be observed that the device described is of a simple, compact nature, and capable of inexpensive manufacture and convenient installation. The arrangement of the oil preheating chamber is such that a satisfactory and efficient heating of the oil takes place while its location below the filter chamber results in a particularly effective filtering step.

I claim:

1. An oil refining device for use in association with an internal combustion engine comprising a cylindrical container having substantially horizontally disposed top and bottom closure members, a partition member in the container spaced a short distance from the bottom member and being slightly inclined with respect thereto, said partition member forming a heating chamber in the bottom portion of the container having a restricted portion and an enlarged portion, an inlet in the restricted portion of the heating chamber for a heating fluid, a substantially horizontally disposed perforated circular plate in the container spaced slightly above said partition member and forming between said plate and partition member an oil preheating chamber having a restricted portion and an enlarged portion, a slightly inclined and substantially circular perforated plate in the container spaced slightly below the top member and forming between said plates a filter chamber occupying the major portion of the container, a body of filtering material in said filter chamber, means for circulating the oil supply of said engine successively through the oil preheating chamber and the filter chamber, said oil preheating chamber having an inlet for said oil supply in the enlarged portion thereof, and an outlet for treated oil communicating with the space between the second perforated plate and the top of the container.

2. An oil refining device as defined in claim 1 including means for supplying hot combustion gases from the exhaust manifold of said engine to the inlet in the restricted portion of said heating chamber, an outlet for said gases in the enlarged portion of said heating chamber, and means for adjustably controlling the flow of gases through said outlet.

3. An oil refining device comprising a cylindrical member, top and bottom closures therefor, a rod extending axially through the cylindrical member and engaging said closures to hold the latter in position on the cylindrical member, a substantially solid partition in said cylindrical member spaced slightly above said bottom closure and slightly inclined with respect thereto, a perforated partition in the cylindrical member disposed slightly above said solid partition and sub-

stantially parallel to the bottom closure, a second perforated partition in the cylindrical member disposed slightly below the top closure and slightly inclined with respect thereto, a body of filtering material substantially filling the space between said perforated partitions, an inlet and an outlet in said bottom closure for a heating fluid, an inlet in said cylindrical member for oil to be treated, said oil inlet being located between said solid and first perforated partitions at a point adjacent the lowermost edge of said solid partition, and an outlet for treated oil communicating with the space between the second perforated partition and top closure.

4. An oil refining device as defined in claim 3, including means for indicating an undue accumulation of oil in said device comprising a conduit communicating with the space between the second perforated partition and top closure and with indicating means responsive to a predetermined amount of oil in said conduit.

5. An oil refining device for use in association with an internal combustion engine comprising a container having top and bottom closure members, a partition member in the container spaced a short distance above the bottom member and forming a heating chamber in the bottom portion of the container, an inlet in said heating chamber for a heating fluid, a perforated partition member in the container spaced slightly above said first partition member and forming between said partition members an oil preheating chamber, a second perforated partition member in the container spaced slightly below said top member and forming between said perforated partition members a filter chamber occupying the major portion of the container, a body of filtering material in said filter chamber, means for circulating the oil supply of said engine successively through the oil preheating chamber and the filter chamber, said oil preheating chamber having an inlet for said oil supply, and an outlet for treated oil communicating with the space between the second perforated partition member and the top member.

6. An oil refining device for use in association with an internal combustion engine comprising a container having top and bottom closure members, a partition in the container spaced a short distance above the bottom member and forming a heating chamber in the bottom portion of the container, an inlet in said heating chamber for a heating fluid, a second partition in the container spaced slightly above the first partition and forming therebetween an oil preheating chamber, a third partition in the container spaced slightly below the top member and forming between the second and third partitions a filter chamber occupying the major portion of the container, a body of filtering material in said filter chamber, said second and third partitions each having passages for oil extending therethrough, means for circulating the oil supply of said engine successively through the oil preheating chamber and the filter chamber, said oil preheating chamber having an inlet for said oil supply, and an outlet for treated oil communicating with the space between the third partition and the top member.
